JAMES H. VAUGHAN, OF OAKLAND, CALIFORNIA.

STIPPLING-PEN.

1,153,468.

Specification of Letters Patent. Patented Sept. 14, 1915.

Application filed October 19, 1914. Serial No. 867,453.

To all whom it may concern:

Be it known that I, JAMES H. VAUGHAN, a citizen of the United States, residing at Oakland, in the county of Alameda and 5 State of California, have invented new and useful Improvements in Stippling-Pens, of which the following is a specification.

This invention relates to a stippling pen which is particularly adapted for drawing 10 plans where concrete is used. It will fill in the drawings of forms, piers, walls, etc., and is also very useful in topographical work as it can be used to show trees, brush, swamp lands, fences, etc.

15 The object of the present invention is to provide a pen of the character described which is operated by an electric magnet with connected armature; and another object of the invention is to provide an automatically 20 actuated switch for interrupting the current flow through the magnet.

Another object is to provide means for adjusting and cushioning the stroke of the pen.

25 Further objects will appear hereinafter. The invention consists of the parts and the construction and combination of parts as hereinafter more fully described and claimed, having reference to the accompanying 30 drawings in which—

Figure 1 is a central vertical section through the device at the instant of attraction of armature and opening the switch. Fig. 2 is a cross section on line 2—2, Fig. 1.

35 More specifically described, the pen as a whole consists of a casing A in which is mounted a magnet coil 2, the core 3 of which is hollow. Extending through said hollow core is a driving rod 4, on the upper end of 40 which is secured an armature 5 which is disk shaped.

Slidably mounted on the driving rod, between a shoulder 6 in the casing and the lower end of the magnet, is a switch member 45 7 which consists of a soft iron disk 8 surrounded by a platinum ring 9. This ring is adapted to close a circuit through the magnet when brought into engagement with a pair of contact members 10 and 11, and the 50 circuit thus closed will energize the core and attract or hold the soft iron disk (or what will be hereinafter termed the "switch armature") with connected platinum ring in engagement with the contact members. The 55 main armature 5 is at the same time attract-

ed by the upper end of the core and will consequently pull the driving rod in a downward direction. The downward movement is, however, limited by a collar 12 formed on the rod which engages with the switch armature and pulls it away from the contact members. The magnet circuit is thus broken and the driving rod will now be returned to its normal upper position by a coil spring 13 which is interposed between a collar 14 60 on the rod and a seat 15 in the casing.

The upward or return movement of the driving rod is transmitted through an adjustable nut 16, mounted on a threaded section 17 on the rod, and a spring 18^a to lift 70 the switch armature, with connected platinum ring, into engagement with the contact members. The circuit through the magnet is thus again closed and the cycle of operation repeated. 75

The current is conducted from any suitable electrical source of supply by wires 18 and 19 to the terminal block 20. One wire is then passed down the side of the magnet and connected with the switch contact 10, 80 while the other wire is connected with the upper terminal of the magnet coil. A connection 21 is then made between the lower terminal of the magnet and switch contact 11. Engagement of the platinum ring, with 85 the contacts, will thus close a circuit through the coil while engagement of shoulder 12, with the switch armature, will automatically break the circuit on the completion of the downward stroke of the driving rod, the 90 circuit being again closed on the return upward movement of the driving rod by spring 18^a, which lifts it into engagement with the contact members. The coil spring simply rests on the adjustable nut and while 95 the pen is not in operation the spring will hold the switch armature against its contacts. When the pen is in operation, this spring is first lowered away from the switch armature, which is now held up by the mag-

net being in operation, giving it room to fall away from the contacts when the circuit is broken by shoulder 12. Nut 16 by being adjusted will change the time that it takes for the switch armature to be closed, as the 100 distance between coil spring 18^a and the switch armature is increased or decreased by the adjustable nut.

The pen proper, indicated at 20^a, is made with fairly wide blades which are set close 110

together. This allows the pen to hold a fair quantity of ink and at the same time prevents splashing of the ink on the paper.

The pen is connected with or attached to the driving rod in the following manner: 5 27 indicates a sliding bearing in the form of a piston, in the lower end of which the pen is secured by means of a nut 22. The lower end of the driving rod enters the upper end 10 of the sliding bearing and is provided with a plunger 23, between which and nut 22 a coil spring 24 is interposed. When at rest, this plunger is pressed up against the upper end of the bearing with a slight pressure. 15 On the down stroke of the pen, when the pen point hits the paper and is unable to go any farther, the plunger in the piston bearing moves down and compresses the spring. This action takes up most of the jar and 20 keeps the pen from driving through the paper. It also allows the driving rod to complete its stroke irrespective of the time that the pen hits the paper.

The exterior casing is preferably reduced 25 in diameter, as indicated at 25 and 26, to produce a grip and shape most convenient for the hand.

The pen constructed as here shown may 30 be used for indicating concrete in forms, piers, walls, etc., and in topographical work for showing trees, brush, swamp lands, fences, etc.

The only change needed to adapt the pen 35 for various kinds of work is a change of position in the hand of the person operating it.

The materials and finish of the several 40 parts of the pen are such as the experience and judgment of the manufacturer may dictate.

Having thus described my invention, what 45 I claim and desire to secure by Letters Patent is—

1. In a stippling pen of the character described, the combination with a casing having 50 a hollow cored electromagnet mounted therein, of a spring actuated driving rod extending through said core, a main armature plate secured to said rod which is adapted to be actuated by the magnet, a pen connected with the driving rod, a pair of contact members with which the terminals of the magnet are connected, a switch armature mounted below said contact members adapted to close a circuit through same, and means 55 for automatically lifting the armature disk up into engagement with the contact members when the magnet is deenergized.

2. In a stippling pen of the character de-

scribed, the combination with a casing having 60 an electromagnet mounted therein, of a main armature plate movable in relation thereto, a spring actuated driving rod connected with the armature, a pen connected with the driving rod, and a switch armature for automatically interrupting the current 65 flow through the magnet and releasing the first named armature.

3. In a stippling pen of the character described, the combination with a casing having 70 a hollow cored electromagnet mounted therein, of a spring actuated driving rod extending through said core, a main armature plate secured to said rod and which is adapted to be actuated by the magnet in opposition to the spring, a pen connected 75 with the driving rod, and a switch automatically actuated by the driving rod for interrupting the current flow through the magnet and releasing the armature.

4. In a stippling pen of the character described, the combination with a casing having 80 an electromagnet mounted therein, of a main armature member movable in relation thereto, a driving rod connected and movable with the armature, a pen connected to 85 said rod, a spring connected with the rod exerting its tension in opposition to the pull of the magnet, and a deenergizing switch actuated by the movement of the rod.

5. In a stippling pen of the character described, the combination with a casing having 90 an electromagnet mounted therein, of a main armature member movable in relation thereto, a driving rod connected with the armature, a pen yieldingly connected to said 95 rod, a spring connected with the rod exerting its tension in opposition to the pull of the magnet, and an armature switch actuated by the outward movement of the rod to release the main armature.

6. In a pen of the character described, a casing, a tubular electromagnet, a reciprocally mounted driving rod in said magnet, an armature carried by said rod, a sliding bearing, a pen secured to said bearing, a coil spring interior of said bearing, a plunger on the driving rod engageable with said spring, and an armature releasing switch and a rod returning spring.

In testimony whereof I have hereunto set 100 my hand in the presence of two subscribing witnesses.

JAMES H. VAUGHAN.
